UNITED STATES PATENT OFFICE

108,577

DESIGN FOR A LIP BRUSH OR SIMILAR ARTICLE

Charles A. Mureau, Los Angeles, Calif.

Application December 22, 1937, Serial No. 73,802

Term of patent 14 years

To all whom it may concern:

Be it known that I, Charles A. Mureau, residing at Los Angeles, in the county of Los Angeles, State of California, have invented a new, original, and ornamental Design for a Lip Brush or Similar Article, of which the following is a specification, reference being had to the accompanying drawing forming a part thereof.

Fig. 1 is a side elevational view of a lip brush or similar article embodying my new design with the cover in closed position, and Fig. 2 is a side elevational view thereof with the cover removed.

I claim:

The ornamental design for a lip brush or similar article, substantially as shown and described.

CHARLES A. MUREAU.
